UNITED STATES PATENT OFFICE.

EDWARD J. PRATT, OF NEW YORK, N. Y., ASSIGNOR TO WESTERN ELECTRIC COMPANY,
INCORPORATED, OF NEW YORK, N. Y., A CORPORATION OF NEW YORK.

REPEATER CIRCUITS.

Application filed September 28, 1922. Serial No. 591,009.

To all whom it may concern:

Be it known that I, EDWARD J. PRATT, a citizen of United States, residing at New York, in the county of New York, State of New York, have invented certain new and useful Improvements in Repeater Circuits, of which the following is a full, clear, concise, and exact description.

This invention relates to repeater circuits, particularly vacuum tube amplifier circuits.

An object of this invention is to provide means whereby an electric discharge electrode and a transmitter may be simultaneously supplied with energizing current from a common source of voltage.

Another object is to provide a simple and efficient arrangement for controlling the gain of a repeater.

In accordance with the embodiment of the invention disclosed, these objects may be accomplished by supplying a telephone transmitter and the cathode of an associated amplifier with energizing current from a common source of voltage. In series with the source of voltage an adjustable resistance may be included for the purpose of varying the current supplied to the transmitter and to the cathode whereby the effectiveness of the amplifier in amplifying the currents impressed by the transmitter upon the amplifier may be varied. In case it is desired to employ a transformer between the transmitter and the control electrode and cathode of the amplifier for stepping up the impedance of the transmitter to an impedance approximating the input impedance of the tube amplifier, the primary and secondary windings of the transformer may have a common terminal so that the transmitter circuit will include the primary winding of the transformer, the adjustable resistance and the battery or other source of voltage, while another current path includes the said battery, the adjustable resistance and the cathode of the amplifier. If desired, the switch for varying the adjustable resistance may be provided with an open circuit stationary contact, so that the movement of the switch arm to this contact simultaneously deenergizes the transmitter and the associated amplifier.

The drawing illustrates this invention embodied in a one stage amplifier.

A vacuum tube or other electric discharge amplifier 7 is disclosed for impressing upon

a telephone receiver 8 amplified currents from the telephone transmitter 9. The control electrode 10 and cathode 11 of the amplifier 7 are connected to transmitter 9 by a step up transformer 12, the primary winding of which is in circuit with transmitter 9 and the secondary winding of which is connected between the cathode and the control electrode. The telephone receiver 8 is included between anode 14 and the cathode 11 by a circuit containing a source of voltage 15 for supplying the output circuit voltage to the amplifier.

This invention provides a circuit whereby the transmitter 9 and the cathode 11 may be supplied with energizing current from a common source of voltage, such as source 16. Source 16 is connected to transmitter 9 by a circuit including the primary winding of transformer 12 and an adjustable resistance 17, contacts to various points on resistance 17 being made by a movable switch arm 18. The source of voltage 16 is also included in circuit with the cathode 11 for supplying heating current to the same, and the amount of the heating current supplied may be regulated by a variation in the position of switch arm 18 to cut in or out more or less of the resistance 17. This arrangement has been found to be a simple and efficient way of varying the gain of the amplifier 7 since considerable variation in the gain of a vacuum tube may be produced by variations in the filament heating current without an appreciable amount of distortion taking place. A variation in the effective value of resistance 17 also varies the intensity of the energizing current supplied to the transmitter, thereby increasing still further the variation in the amplification of tube 7 produced by a change in the position of the switch arm 18.

If desired, an open circuit stationary contact 19 may be provided for switch arm 18 so that the switch arm 18 when in contact with contact 19 simultaneously deenergizes the transmitter and the tube.

It is to be understood that this invention is not limited to any particular type of amplifier or transmitter, nor is the invention limited to an amplifier of a single stage. It will be obvious to those skilled in the art that various modifications of the above disclosure may be made without departing in any wise from the spirit of this in-

vention as defined by the appended claims.

The invention claimed is:

1. In combination, an electric discharge repeater comprising an anode and a cathode, a transmitter coupled to said repeater, an energizing circuit for said transmitter, an energizing circuit for said repeater, and an adjustable resistance common to both of said circuits.
- 10 2. In combination, an electric discharge repeater comprising an anode and a cathode, a transmitter coupled to the input circuit of said repeater, an energizing circuit for said transmitter, an energizing circuit for said cathode, and an adjustable resistance common to both of said energizing circuits.
- 15 3. In combination, an electric discharge repeater comprising an anode, a cathode and a control electrode, a telephone transmitter, a transformer for coupling said transmitter to said control electrode and said cathode, a source of voltage, an adjustable resistance, a series circuit including said transmitter, the primary winding of said transformer, said source and a portion of said resistance, and a second circuit including said cathode, said source and a portion of said resistance.

In witness whereof, I hereunto subscribe my name this 26th day of September A. 30 D., 1922.

EDWARD J. PRATT.
